DESIGN FOR A COMBINED WRENCH STAND AND CASE OR THE LIKE

Sigmund Mandl, Milwaukee, Wis., assignor to Blackhawk Mfg. Co., Milwaukee, Wis., a corporation of Wisconsin

Application February 8, 1937, Serial No. 67,497

Term of patent 7 years

To all whom it may concern:

Be it known that I, Sigmund Mandl, a citizen of the United States and a resident of Milwaukee, in the county of Milwaukee and State of Wisconsin, have invented a new, original, and ornamental Design for a Combined Wrench Stand and Case or the like, of which the following is a specification, reference being had to the accompanying drawing, forming a part thereof.

Figure 1 is a perspective view of a combined
wrench stand and case embodying my design;
and

Figure 2 is a view thereof in opened position.
I claim:

The ornamental design for a combined wrench stand and case or the like, as shown.

SIGMUND MANDL.
